UNITED STATES PATENT OFFICE.

RUDOLPH SCHWARZ, OF PITTSBURGH, PENNSYLVANIA, ASSIGNOR, BY MESNE ASSIGNMENTS, TO WILLIAM FULD, OF BALTIMORE, MARYLAND.

DESIGN FOR A ROCKER.

Application filed April 24, 1923. Serial No. 5,927. Term of patent 7 years.

To all whom it may concern:

Be it known that I, RUDOLPH SCHWARZ, a citizen of the United States, residing at 304 Atwood Street, Oakland, Pittsburgh, in the county of Allegheny and State of Pennsylvania, have invented a new, original, and ornamental Design for Rockers, of which the following is a specification, reference being

had to the accompanying drawing, forming part thereof, in which—

The figure is a perspective view of a rocker showing my new design.

I claim:—

The ornamental design for a rocker as shown.

RUDOLPH SCHWARZ.
